COATING APPARATUS

Ralph W. Hodil and John C. Redmond,
Youngstown, Ohio

Application May 8, 1940, Serial No. 333,982

3 Claims. (Cl. 91—12.5)

This invention relates to the art of coating and, in particular, to the coating of metal as by galvanizing or the like.

In the galvanizing of metal articles, such as sheets or strip by the conventional hot-dip process, the level of the coating bath of molten zinc at the exit rolls is one of the factors which control the thickness of the coating formed on the base metal. In order that the product shall be uniform in respect to the thickness of the protective metal coating applied thereto, the level of coating bath should be accurately controlled. It has been the practice heretofore to replenish the supply of coating metal as consumed, by adding solid spelter to the bath. Obviously this procedure is not well adapted to a close regulation of the level of the coating bath. We have invented a novel apparatus for controlling the level of the coating bath in a galvanizing apparatus, which is effective to maintain the level at the desired point within narrow limits, regardless of consumption of the coating metal or replenishment of the supply thereof.

In a preferred embodiment and practice of our invention, we provide a displacement member adapted to be lowered into the bath or lifted therefrom as may be necessary, to maintain the surface of the bath at the proper level. We also provide automatic means responsive to the level of the bath for correcting any departures from a predetermined normal level.

The aforementioned preferred embodiment and practice of the invention are illustrated more or less diagrammatically in the accompanying drawing and will be described and explained in detail hereinafter, with reference thereto. In the drawing,

Fig. 1 is a longitudinal section through a galvanizing machine incorporated our invention; and

Fig. 2 is a transverse section therethrough taken along the plane of line II—II of Fig. 1.

Referring now in detail to the drawing, a galvanizing pot 10 is provided with the usual rig 11 including spaced side frames in which are journaled entry rolls 12, bottom rolls 13 and exit rolls 14. Guides 15 direct sheets emerging from a flux tank between the entry rolls. From the entry rolls the sheets are directed by guides 16 between the bottom rolls and thence by guides 17 between the exit rolls which remove excess coating material from the sheets. The several sets of rolls are mounted and driven in the customary manner.

While we have shown in the drawing, by way

of example only, a sheet galvanizing machine, it will be understood that the invention may also be incorporated in strip-galvanizing apparatus.

In order to apply the proper coating to the sheets traversing the pot, the level of the molten zinc therein should be maintained at about the height indicated by the chainline 18. The level may be raised or lowered slightly, however, if it is desired to vary the thickness of the coating applied. In order to maintain the level of the coating bath at a predetermined height, we provide a displacement member or weight 19 adapted to be immersed in the bath to a greater or less extent. The member 19 may conveniently be of box-like formation as shown and should be of such weight as to displace the molten zinc readily. The member 19 is reciprocable vertically between guides 20, the sides of the member being recessed as at 21 to receive the guides. The guides are secured to bridge angles 22 extending across the pot 10 and resting on supporting yokes 23 carried thereon.

A base plate 24 is secured to the angles 22 and provides a support for a bearing casting 25. A jack screw 26 secured to the member 19 extends upwardly through the bearing casting 25 being guided for vertical movement by spaced eyes 27 formed therein. A worm wheel 28 is positioned between eyes 27 and has a threaded bore for receiving the screw 26.

The casting 25 is also provided with bearings 29 for a worm shaft 30. A worm 31 on the shaft 30 meshes with the wheel 28. A motor 32 mounted on the base plate 24 is coupled to the worm shaft 30 by a coupling 33.

It will be understood that the operation of the motor 32 in one direction or the other will effect vertical adjustment of the displacement member 19 by rotation of the worm wheel 28 through which the screw 26 is threaded.

The motor 32 may be of any suitable type and is provided with the necessary control equipment whereby it may be started, stopped and reversed as desired. For purpose of illustration, however, we have shown a motor 32 as of the double field winding, series type. In any event, the motor is controlled by a float switch mechanism indicated generally at 34. This mechanism comprises a pair of vertically spaced fixed contacts 35 and 36. Cooperating with these contacts is a moving contact 37 mounted on a rod 38 extending upwardly from a float 39 immersed in the bath. The rod 38 is guided for vertical movement in a bracket 40 secured to one of the yokes 23. The contact 37, furthermore, may be ad-

justable on the rod 38 as by means of a set screw or the like.

In the drawing, contact 37 is illustrated in median position between the contacts 35 and 36. It will be apparent, however, that the contact 37 will engage one or the other of the contacts 35 and 36 upon a sufficient departure of the level of the coating bath from the normal level 18. If it is assumed, therefore, that the level of the coating metal falls, as it does in practice because of the removal of coating metal by the sheets passing through the bath, the contact 37 will ultimately engage the contact 36. This closes an energizing circuit for the motor 32 from one side of a supply line 41, through the contacts 37 and 36 and thence through one of the field windings of the motor 32 and its armature, in series, thus driving the motor 32 in one direction. Connections to the motor, of course, will be so made that on engagement of the contacts 37 and 36 the motor is driven in the direction necessary to lower the displacement member 19.

As the member 19 is lowered by operation of the motor 32 as described above, the amount of molten coating metal displaced thereby is increased and the level of the metal in the tank is raised accordingly. The raising of the level of the bath lifts the float 39 and thereby causes separation of contacts 37 and 36. This terminates the corrective operation for the time being. Whenever the level of the bath falls further, however, the operation is repeated.

It is necessary at intervals to replenish the supply of molten coating metal in the pot 10. This may be done in the usual manner by adding solid spebler to the bath. The apparatus of our invention immediately accommodates itself to the resulting change in the level of the coating bath. Addition of fresh coating metal will naturally tend to raise the level of the bath and also the float 39. As a result, the contact 37 engages the contact 35 and, in the manner already described, causes operation of the motor 32 but this time in the reverse direction. The displacement member 19 is thus raised, decreasing the amount of molten metal displaced thereby and lowering the level of the bath until the descent of the float 39 causes the contact 37 to separate from the contact 35.

It will be apparent from the foregoing description that the invention operates automatically to maintain the desired level of the coating bath at all times and immediately corrects departures from the predetermined level whether a fall resulting from consumption of the metal or a rise

resulting from pouring in fresh metal. By reason of this automatic maintenance of the proper level of the metal in the pot, the material passing therethrough is coated to a uniform thickness. The invention also lends itself readily to controlling the thickness of the applied coating. Adjustment of the contact 37 on the float rod 38 will obviously cause a corresponding adjustment of the level of the floating metal. If it is desired to apply a thicker coating, therefore, it is only necessary to adjust the contact 37 so that it maintains the coating metal at a level somewhat above that indicated at 18, and vice versa, thus making it unnecessary to pour in or dip out substantial quantities of zinc in order to change the thickness of the applied coating.

The invention is simple in construction and effective in operation, requiring little or no maintenance.

Although we have illustrated and described but a preferred embodiment and practice of the invention, it will be understood that changes in the construction and procedure disclosed may be made without departing from the spirit of the invention or the scope of the appended claims. While the invention has been described with particular reference to the galvanizing of sheets, it is also applicable to other coating operations and to other classes of material.

We claim:

1. Coating apparatus comprising a coating bath, a displacing member adapted to be submerged in the bath, means for varying the submergence of said member, and means actuated in accordance with changes in the level of the bath for controlling said last-mentioned means to raise or lower said displacing member.

2. Coating apparatus comprising a coating bath, a displacing member adapted to be submerged in the bath, means for varying the position of said member vertically, and means actuated in accordance with changes in the level of the bath for controlling the last-mentioned means to raise or lower said displacing member.

3. In a galvanizing apparatus, a zinc bath, a displacing member adapted to be lowered into the bath as the zinc is consumed to maintain the level thereof at a predetermined height and to be raised as zinc is added, means for varying the position of said member, and a float switch actuated in accordance with changes in said level for controlling said means to raise or lower said displacing member.
